READING AID FOR THE BLIND

Leslie E. Flory, Princeton, N. J., assignor to Radio Corporation of America, a corporation of Delaware

Application November 29, 1946, Serial No. 713,175

14 Claims. (Cl. 179—1)

1. This invention relates to recording and reproducing devices and in particular to a device in

which a punched or printed tape is used to control the artificial reproduction of sound.

The use of mechanical recording systems as reading aids for the blind is well known. Books and other literature are recorded by any of the well known methods and the recorded material is then reproduced audibly by a suitable device. The present invention contemplates artificially reproducing speech by first recording, by any conventional means, the basic tones or sounds which comprise the spoken language, and then selecting and combining the sound components in a controlled time sequence to reproduce artificially intelligible words. Further, the selection and sequence of the basic sound components is to be accomplished by a control or programming device containing coded indicia which can be prepared by hand or by a simple printing or punching machine. It is thus possible to "write" a message to a blind person, which message will then be reproduced audibly by the device. It is therefore the primary object of this invention to convert coded manually formed indicia into corresponding intelligible sound, it being understood that the term "manually formed indicia" includes printed, stamped or perforated indicia of all types in contradistinction to recordings which in themselves contain the form of the sound waves, examples of the latter being the conventional recording on wax discs or cylinders, sound recording on films or magnetic tape recording.

All the words of a given language are formed by different sequences of one or more basic sound components. While there are, undoubtedly, a very large number of basic tones or sounds in normal speech with all its degrees of inflection and accent, linguists agree that intelligible speech can be reproduced by the proper combination of only 35 different basic sounds. While this invention is not limited to this figure, purely for the purpose of illustration it will be assumed that the generation of 35 unique sounds will be sufficient. If the acquired skill of the user makes possible intelligible communication with fewer basic sound components, or if a greater number of basic components are desired for greater fidelity, the necessary modification of the apparatus will be apparent to one skilled in the art.

In brief, the above objects are achieved by recording the 35 basic sounds, selecting them in a sequence determined by a simple programming device, and combining the selected sounds to form intelligible speech. Further, it is also contem-

plated that complete words may be recorded, and the programming device used to form sentences directly. Of course, the latter system has its primary application to annunciator systems where a very limited vocabulary is employed. Consequently the sound-representing components of speech which are recorded may comprise complete words or the unique sound components of which words are formed.

2. It is a further object of this invention to provide an improved programming system for controlling by coded indicia the sequential application of a plurality of sources of energy to a utilization device.

3. A still further object of this invention is to provide a programming device in which a relatively few distinctive indicia uniquely control a larger number of operable elements.

4. The novel features that are considered characteristic of this invention are set forth with particularity in the appended claims. The invention, both as to its organization and method of operation, as well as additional objects and advantages thereof, will best be understood from the following description when read in connection with the accompanying drawings, in which

Fig. 1 is a view partly in cross-section of a portion of this invention;

5. Fig. 2 is a view illustrating the method of controlling the operation of the tone wheels;

6. Fig. 3 is a circuit diagram illustrating the method of connecting the phototubes illustrated in Fig. 1;

7. Fig. 4 is a circuit diagram of a portion of the programming circuit;

8. Fig. 5 is a view of the programming tape showing the coded indicia;

9. Fig. 6 is a circuit diagram of a rectifier utilized in the arrangement illustrated in Fig. 4;

10. Fig. 7 is a circuit diagram of the remaining portion of the programming circuit which is used in conjunction with the portion illustrated in Fig. 4;

11. Fig. 8 illustrates an alternative embodiment of this invention in which continuously rotating tone wheels are employed;

12. Fig. 9 illustrates the use of a special cathode ray tube to produce the speech components in lieu of the rotating tone wheels, together with the control circuit therefor;

13. Fig. 10 is an enlarged view of a portion of the target of the cathode ray tube illustrated in Fig. 9;

14. Fig. 11 is the circuit diagram of a slide-back trigger circuit in accordance with the prior art;

Fig. 12 illustrates a modified cathode ray tube with individual grid selector elements for controlling the vertical displacement of the beam in generating the different speech component signals; and

Fig. 13 illustrates a method of controlling the application of biasing potentials to the selector grid of the device illustrated in Fig. 12.

Similar reference numerals apply to similar parts throughout the several figures of the drawings.

A plurality of separate sound generators of any suitable type are provided for producing respectively distinctive oscillatory vibrations corresponding to the sound-representing components of speech. In Figs. 1 and 2 for example, 35 tone wheels 1 are employed, although for simplicity only three have been illustrated. Since all units are identical except for the nature of the sound recorded on each, it will only be necessary to describe one of them. The tone wheel 1 is rotatably mounted on a shaft 3 driven at a constant speed by a motor 5. Each tone wheel 1 is normally prevented from rotating by a pin 7 which is moved from engagement with the wheel by a tripping relay 9 of which it is a part. When current is applied to the coil 11 of relay 9 the pin is momentarily raised, permitting the disc 1 to rotate once in response to the torque applied by a friction clutch plate 13 which is held against the disc and rotated by a spring 15, one end of which is firmly anchored on the shaft 3. A thrust bearing 17 is provided for each disk to hold it in position.

One of the 35 distinctive sounds is recorded photographically near the circumference of the disc 1, as shown at 19 in Fig. 2. The sound may be reproduced by means of a light source 21 and a phototube 23 associated with each disc. The phototubes 23 are connected as shown in Fig. 3 although, for simplicity, only 3 of the 35 tubes have been illustrated. The tubes are all connected in parallel, a bias cell 25 being connected between anode and ground and output being developed across an output resistor 27 connected between cathode and ground. An amplifier 29 applies the audio signal to a loudspeaker or headset 31.

The control or programming system for operating the tripping relays in a desired predetermined sequential order will now be described.

Referring to Figs. 4 and 5, the image 33 of a slit of light is projecting by a suitable source 35 on a paper tape 37. The paper tape is moved in a direction perpendicular to the slit at a constant rate by any suitable drive mechanism, not shown. The paper tape has printed thereon two series of indicia which may comprise transverse bars 39a and 39b, each bar being from 0 to 5 units in length. The bars have distinctive light reflecting properties with respect to the paper tape, or may comprise perforations of different effective areas. In any case, two phototubes 41 and 43 are suitably disposed with respect to the tape, so that each tube is responsive to the six degrees of light reflected from or transmitted through the paper at any instant at the region then lying under respective halves of the image 33.

It will be observed that, including zero, there are six indicia lengths or six degrees of light intensity which will produce corresponding current intensities in each phototube. Considering all possible variations of indicia, there are 36 unique combinations which can be made by combining one indicium of the first series with one

of the second series. Eliminating the "zero-zero" combination, since it is the same as a space, there result 35 unique coded combinations available for use. Thus the 35 unique combinations 5 of an indicium of the first series with an indicium 10 of the second series will be used to operate the 35 sound generators. It should be noted that with only n variations in the form of the indicia, approximately n_2 generators can be controlled 15 independently. Also it should be noted that the tape can readily be printed or punched by hand, or by a simple perforating or printing machine, with only 5 different characters or shapes (not counting zero), and yet 35 tones can be controlled 20 from which intelligible speech can be produced. A few typical combinations are shown on the right hand portion of the tape 37 in Fig. 5.

Referring again to Fig. 4, the output of phototube 43 is amplified by an amplifier 45 and applied 25 to the control grid of a reactance tube 47 which is connected across the tank circuit of an oscillator 49 in conventional manner. The phototube 41 is identically connected to another amplifier, reactance tube and oscillator, shown as 30 a block diagram 51 for simplicity.

The output of oscillator 49 is coupled to the parallel-connected grids of six coupling tubes 53a, 55a, 57a, 59a, 61a, and 63a. The output circuits 35 of these tubes includes six band pass filters, 65a, 67a, 69a, 71a, 73a, and 75a, respectively. The six band pass filters are connected to six rectifiers, 77a, 79a, 81a, 83a, 85a and 87a, respectively. The output of each rectifier is available between ground and six output terminals of group a 39a, 91a, 93a, 95a, 97a, and 99a. The output of 40 the second amplifier-oscillator 51 is connected in an identical manner to six coupling tubes, band pass filters and rectifiers to six output terminals of group b. For purposes of identification similar reference numerals of the two groups have corresponding subscripts.

The operation of the device so far described is as follows: The output of phototube 43 varies 45 through six discrete steps as the indicia of the first series pass under the light image. The current variations control the grid voltage of the reactance tube 47 through a range of values which cause the oscillator frequency to vary in like steps between two predetermined values which may be, for example, from 1000 to 1250 k. c. The six 50 band pass filters of each group are each tuned to pass one frequency in this range, preferably in 50 k. c. steps, i. e., 1000, 1050, 1100, 1150, 1200 and 1250 k. c. respectively. Consequently for each 55 indicium of the first series a D. C. voltage will appear at one and only one of the a group output terminals 89a, 91a . . . 99a, while a similar voltage will appear at one of the b group of terminals as determined by the indicium of the second series scanned concurrently. Thus there 60 will be 35 unique combinations of voltages, excluding the case in which both indicia are zero.

The circuit of each rectifier is shown in Fig. 6. Input is applied between ground and the anode of a diode 101, the cathode being connected 65 to ground by a resistor 103. The rectified pulse charges capacitor 105 through resistor 107, the time constant of the circuit being such that the capacitor is completely discharged before the 70 next successive control signal arrives.

The circuit for combining the two control signals to operate one relay for each unique combination is illustrated in Fig. 7 in which the twelve output terminals of Fig. 4 are shown. A 75 resistance matrix 109 is utilized which comprises

twelve vertical and 35 horizontal conductors interconnected by resistors in a manner to be described. It is to be understood, of course, that the orthogonal arrangement of the conductors is purely for convenience of illustration, the only operational requirement being that the circuits are connected as shown.

The twelve vertical conductors are connected, respectively, to the twelve input terminals 89a to 89a and 89b to 99b. The 35 horizontal conductors are connected to the grid electrodes of 35 amplifier tubes 111, respectively. The cathode electrodes of all amplifier tubes are connected together and to ground through a bias battery 113 which provides a positive cathode bias. Each horizontal conductor is connected by a resistor of relatively high value, say 500,000 ohms, to one vertical conductor of each group. However, no two horizontal conductors are connected to the same two vertical conductors. Also, since the combination "zero-zero" is not used, there is no tube whose grid is connected to both terminals 89a and 89b. One of the 35 tripping relays 19 is connected in the plate circuit of each tube 111, in this instance all 35 tubes and relays being shown. It is understood that the solenoid 11 of each relay 9 is serially connected between the respective plate electrodes and a common source of plate potential available at terminals 115 and 117.

It will be observed that the grid of each tube 111 is connected to the midpoint of two resistors which terminate at one terminal of the a group and one terminal of the b group. For example, the grid of tube 119 is connected to the midpoint of resistors 121 and 123, which connect to terminals 89a and 91b, respectively.

Assuming that the corresponding indicia on tape 31 have caused positive potentials to appear on these terminals, the grid of tube 119 will have the same value, say +1.5 volts, for example. The value of the bias voltage produced by battery 113 has a value of, say, 1 volt and the tube conducts, causing the associated relay 9 to operate, and the first tone disc 1 rotates once. If, however, there is a positive potential on only one of the two terminals, the other being essentially grounded through resistor 107 of the rectifier, which preferably has a low value as compared to the matrix resistors, then the grid voltage will be only +.75 volt, which is insufficient to overcome the 1 volt bias, and the tube remains cut off. Thus it can be seen that for each unique combination of indicia one and only one relay will operate, thus controlling the operation of the tone discs in the sequence determined by the coded indicia on the tape.

An alternative embodiment of this invention is illustrated in Fig. 8. The programming arrangement illustrated in Fig. 4 is employed, as before. Also, as before, the twelve terminals of groups a and b are connected to an identical resistance matrix 109, as in Fig. 7, the horizontal conductors of which connect to the grid electrodes of 35 tubes 111, only 3 of which are now illustrated, since all the others are identical. However, the tripping relays 9 and the mechanical starting system for the tone wheels 1 are replaced by a wholly electronic control. Thus, in Fig. 8, the 35 tone wheels 1 are now fixedly mounted on shaft 3 and all are rotated continuously. As before, each recorded sound track is scanned by a phototube 23, the output of each phototube being coupled to the grid of one of the amplifier tubes 111. The plate electrodes of all

tubes 111 are connected together and through an output resistor 125 to the source of plate potential at terminal 115. A utilization device 127 is coupled to the output resistor to convert the modulated electrical currents into audio sound of suitable amplitude. As before, the cathode electrodes of tubes 111 are connected to ground through a biasing battery 113.

In operation, one tube 111 at a time becomes operative and passes a modulated audio tone to the utilization device, the sequence being determined by the indicia on the tape of the programming device. All other tubes are biased off and pass no audio signal to the output. The time interval during which the conducting tube remains operative should be equal to the time required for the tone wheel to make one revolution. This may be accomplished by adjustment of the time constant of the rectifier resistors 103 and 107 with respect to capacitor 105, or, alternatively, if output potential from resistor 103 is taken directly, effectively short-circuiting capacitor 105, the length of each pulse can be controlled by the width of the indicia 39 or the speed of the tape 31.

A wholly electronic reproducing system is illustrated in Fig. 9. As before, the programming arrangement of Fig. 4 is utilized, the modification being in the portion of the system following the 25 a and b groups of terminals 89 to 99. The a group less the "zero" terminal 89a, which is not used, is connected to the grid electrodes of 5 control tubes 129, 131, 133, 135 and 137, while the six b groups of terminals are connected, respectively, to the grid electrodes of six additional control tubes 139, 141, 143, 145, 147 and 149.

The cathode electrodes of the 11 control tubes are connected to ground through 11 resistors 151 to 179, respectively, each having a different value 40 as will appear subsequently. The plate electrodes of all tubes are connected together. Plate potential is applied through a load resistor 173 from terminal 115. The plates are also connected to one vertical deflecting plate 175 of a cathode ray tube 177 and coupled through an 45 amplifier 179 to a trigger circuit 181, the output of which is connected to one horizontal deflecting plate 183 of the cathode ray tube 177. The remaining deflecting plates are connected to potentiometers 185, 187 which are used to center the electron beam.

The cathode ray tube 177 includes a special target electrode 189 provided with 35 distinctive masks 191₁ to 191₃₅ extending laterally across the target, as shown in greater detail in Fig. 10. Each mask is shaped in a predetermined manner so that as the electron beam sweeps horizontally along the mask the target is shielded from the beam to a greater or less extent. The variations of the shield are recorded representations of the 55 35 basic sounds and may, for example, comprise sections of variable area sound film. These recordings may be printed directly on the target by known photographic methods. The target 60 may be of secondary-electron emissive material. In any event, the potential of the target varies in accordance with the variation in the number of electrons striking it. The oscillatory sound-representing potential of the target is applied to the grid of an amplifier 193 and reproduced by a loudspeaker, headset 195, or the like. Although the size of the drawing does not permit illustration of the 35 different masks, it will be understood that these may readily be provided. 65 The selection of the desired sound is accom-

plished by deflecting the beam vertically. This is the function of the control tubes 129 to 149. Remembering that only one tube of *a* group and one tube of *b* group will be operative at a given time, let us assume that positive potentials are applied to terminals 91a and 89b to make tubes 129 and 139 conductive. Cathode resistors 151 and 161 are then adjusted to values which cause the common plate potential, which is applied to deflecting plate 175, to have the value necessary to deflect the beam upwardly to the first line 191₁. For the combination of tubes 131 and 139, the value of cathode resistor 153 is made somewhat lower so that more current flows through output resistor 173 and the deflection voltage is that required to drop the beam onto the second line 191₂. Similarly, for the other three control tubes of group *a* considered with the same tube 139 of group *b* the cathode resistors 155, 157 and 159 being adjusted to deflect the beam to the third, fourth and fifth lines, respectively. Considering the *a* group tubes with the second *b* group tube 141, the cathode resistor 163 of the latter tube is adjusted to focus the beam on the sixth line 191₆ in conjunction with the first tube 129 of *a* group. Successive *a* group tubes thus each lower the beam one more line, as before, until line 191₁₀ is reached. The remaining control tubes of group *b* are adjusted similarly, each *b* group tube producing a change of 5 lines more than the preceding one, and each *a* group tube producing a change of one line more than the preceding one. There will therefore be a total of 35 distinct vertical positions of the beam corresponding to and coinciding with the 35 sound tracks of the target from 191₁ to 191₃₅.

Finally, it is necessary to provide means for scanning each line from left to right, for example, once just after the vertical line selection has been accomplished. This function is accomplished by the amplifier 179 and the trigger circuit 181. The amplifier is coupled to the combined plate circuit of the control tubes by a capacitor which applies a pulse to the amplifier as the vertical deflecting voltages are successively applied to the cathode ray tube 177. This pulse is amplified to the extent necessary to produce a short output pulse of the amplitude required to saturate the trigger tube for the smallest input voltage. The trigger circuit 181 is shown in detail in Fig. 11, and comprises a discharge tube 197 having its grid coupled to the output of amplifier 179 by a capacitor 199. The plate circuit includes a shunt capacitor 201 which is charged by a battery 203 through a resistor 205. Output is taken across the capacitor. The change in the voltage applied to the vertical deflecting plate to adjust the beam to the desired vertical position causes a short pulse of positive potential to be applied to the grid of trigger tube 197. The tube is normally biased to cut off by bias battery 207, or the equivalent. Assuming that the capacitor 201 has had time to become fully charged, a positive voltage equal to the battery 203 voltage is normally applied to horizontal deflecting plate 183 and the beam rests at or beyond the left hand edge of the target. The pulse suddenly saturates tube 197, discharging capacitor 201 and causing the beam to move to the right hand edge of the target at a very high rate. The tube then goes to cut-off, the capacitor begins to charge at a relatively slow rate, while the beam moves relatively slowly back to its starting position. In the meanwhile the beam has found its vertical position, so that

it sweeps along or scans the desired sound track and produces a modulated output signal corresponding to the desired sound component of speech. The time constant of the trigger circuit is determined by resistor 205 and capacitor 201. These are selected to produce a scanning rate which produces the desired sound. Of course the scanning rate is less than the interval between successive control signals from the programming circuit so that the selected line is scanned completely before the next pulse arrives. Alternatively, tube 197 may be a gas-discharge type tube. The drop in plate voltage due to the large current through the resistor 205 is effective to extinguish the tube and permit the grid to regain control.

It will therefore be seen that the electronic generator produces under the control of the programming device a succession of audio sound components whose time sequence is determined by the coded indicia of tape 39 so as to produce by their successive combination the desired audible sounds.

In order to provide more accurate control of the vertical displacement of the beam so that the device will be free from small variations in the amplitude of the applied potentials which otherwise might deflect the beam to a position intermediate two line traces, the device illustrated in Figs. 12 and 13 may be employed. As in the preceding cases, the programming device of Fig. 4 is utilized in its entirety so that combinatorial arrangements of the two series of voltages available at the 12 terminals 89a to 99a and 89b to 99b may be employed. These voltages are utilized to control the vertical selection of the 35 positions of the target, in accordance with the principle employed in the "Selectron" fully described and claimed in a copending application of J. A. Rajchman, application Serial No. 665,031, filed April 26, 1946 now Patent No. 2,494,670, granted January 17, 1950.

Referring particularly to Fig. 13, 35 horizontal grid wires 205₁ to 205₃₅ inclusive are arranged in front of the target electrode 189. The 35 grid wires are connected to 35 conductors of a resistance matrix 207. Orthogonal components of the resistance matrix comprises two groups of 6 conductors each. The 6 conductors of the *a* group are connected, respectively, to the movable contacts arm of 6 single pole double throw switches 209, 211, 213, 215, 217 and 218 while the 6 conductors of the *b* group are similarly connected to the movable element of 6 additional single pole double throw switches bearing the same reference numerals but identified by a subscript *b*. One contact terminal of each of the 12 switches is connected to a suitable source of negative potential available on conductor 211 while the remaining contact of each of the 12 switches is connected to a source of positive potential available on conductor 223. The switches are normally biased in one position and are moved to the other position by 12 actuating coils which are connected, respectively, to the 12 output terminals of Fig. 4, 89 to 99 and to ground through a common resistor 225.

As described in the copending application of Rajchman referred to above, electrons directed toward the target are permitted to pass through the "gate" between the grid wire and reach the target only when two adjacent wires are biased to an "opening" potential which may be cathode potential or a positive potential, depending on

the type. Electrons will be turned back and prevented from passing between two negatively biased grid wires, or between one having an "opening" bias and an adjacent wire having a negative bias. It is to be understood that in accordance with the Rajchman application, the grid wire construction may embody either the potential barrier or the deflection type of operation. In the former case, each grid wire 205 will be in register with a positively biased accelerating grid wire positioned between it and the source of electrons. In the latter case, the grid wires will have sufficient width in the direction of the electron beam axis so that the electrons will be controlled in accordance with the established theory of operation. In order not to confuse the drawings, these accelerating grid wires, or the equivalent construction, have not been shown.

In response to the operation of the programming circuits, described above, one switch of each group will be operated to connect, through the resistance matrix, two adjacent grid wires to the relatively positive conductor 223 for each unique combination of the 35 possible combinations. Thus for each combination one and only one gate will be opened between adjacent grid wires, thus assuring accurate and positive control of the electrons so that they will impinge on the desired recorded area of the target.

Fig. 12 shows a cathode ray tube 227 embodying a target 189 and control grid operating on the Selectron principle. The control grid is not shown in detail in Fig. 12, but is indicated merely by a plurality of horizontal grid wires 205, it being understood that the complete operating circuit will be as described above in connection with Fig. 13. The tube includes a conventional beam forming device indicated by a cylinder 229 and also includes 4 conventional deflecting electrodes for controlling the vertical and horizontal movement of the beam. Since the actual vertical selection is accomplished by the selecting grid 205 it is, in the present case, only necessary to deflect the beam vertically at a continuously high rate, the rate preferably being substantially higher than any recorded frequency. This is accomplished, for example, by connecting the output of a 10 k. c. generator 231 between ground and the vertical deflecting plate 175, the complementary vertical deflecting plate being connected to a potentiometer 187 as before. Horizontal deflection across the selected recorded area of the target is accomplished by means of an amplifier 178 and trigger circuit 181 as in the modification illustrated in Fig. 9. Since this device is to cause the beam to move once in a horizontal direction from right to left across the target, each time one of the 35 scanning areas has been selected, the control pulse for the trigger circuit may be derived from terminal 233 (Fig. 13) which is connected to the ungrounded terminal of resistor 225 in series with the actuating coils of the relays which control the potential of the horizontal grid elements. Thus, each time the indicia of the tape 37 move into the field of the illuminated area 33, two of the control relays (one in each group) are operated to select the required line to be scanned, and a pulse is generated across resistor 225 which is amplified and applied to the trigger circuit 181 to cause the electron beam to scan the selected recorded area once and return to its initial starting point ready for the next excursion. As before, output is derived from target 189 by an amplifier 193 and successive 75

sound components representing intelligible speech are available at the output device 195.

What I claim is:

1. In a device of the character described, a plurality of tone generators for producing respectively distinctive audio frequency oscillatory vibrations, and control means for causing said generators to become successively operative in a predetermined time sequence, said control means comprising relatively movable control and responsive elements, said control element having recorded thereon two separate series of coded indicia and said responsive element being separately responsive to each series, said responsive element being connected to initiate operation of each said generator only in response to a unique combination of one indicia of each of said series.
2. A device of the character described in claim 1 in which each series of indicia comprises n distinctive indicia to provide approximately n^2 unique indicia combinations for controlling approximately n^2 generators.
3. A device of the character described in claim 1 in which said distinctive oscillatory vibrations are representative of the basic sound components of normal speech.
4. In a device of the character described, a plurality of tone generators for producing, respectively, distinctive audio frequency sound-representing electrical oscillations, a utilization device, switching means for each generator for applying said oscillations individually to said utilization device, a control element having recorded thereon two separate series of coded indicia, means separately responsive to each of said series for producing a separate control voltage corresponding to each indicium, and means for actuating each of said switching means by a unique combination of a control voltage corresponding to an indicium of each series of indicia.
5. A device of the character described in claim 4 in which n distinctive indicia in each series controls approximately n^2 separate switching means and thus n^2 generators.
6. A device of the character described in claim 4 in which said means for actuating each of said switching means includes a resistance matrix.
7. A device of the character described which includes a plurality of electrical signal supply circuits, a signal utilization device and switching means for each electrical supply circuit for connecting said circuits individually to said device, a control element having recorded thereon two separate series of coded indicia, means separately responsive to each of said series for producing a separate control voltage corresponding to each indicium, said control element and said responsive means being relatively movable, and means for actuating each of said switching means by a unique combination of a control voltage corresponding to an indicium of each series, whereby said circuits are connected individually to said device in a time sequence determined by said coded indicia.
8. In a device of the character described, a plurality of tone generators for producing respectively distinctive audio frequency electrical oscillations, a utilization device, switching means operatively connected with each generator for applying said oscillations individually to said utilization device, a control element having recorded thereon two separate series of coded indicia, means separately responsive to each of said series for producing control voltages which vary in

accordance with said indicia, respectively, means for establishing relative movement between said control element and said responsive means, a pair of oscillators, means for varying the frequency of said oscillators in accordance with the variations of said control voltages, respectively, means including a plurality of band pass filters coupled to each of said oscillators for producing a separate voltage corresponding to each indicium, and means for actuating each of said switching means by a unique combination of a voltage correspondingly to an indicium of each series of indicia, whereby said oscillations are applied to said device in a time sequence determined by said coded indicia.

9. A device of the character described in claim 4 in which said generators are constituted by a target of a material having a given secondary-electron emissive characteristic having thereon distinctive regions of a different secondary-electron emissive characteristic varying in area in predetermined patterns, and means for scanning said regions with an electron beam, and wherein said switching means includes means for selectively moving said beam from one to the other of said regions.

10. A device of the character described comprising a control element having recorded thereon two separate series of coded indicia, means separately responsive to each of said series for producing a separate control voltage corresponding to each indicium, said control element and said responsive means being relatively movable, a cathode ray tube having a target of a material having a given secondary-electron emissive characteristic, means controlled by unique combinations of said control voltages for causing said beam to impinge on given distinctive regions of said target, and to sweep once over the length of said region, means for causing the potential of said target to vary at distinctive audio frequencies as a function of the instantaneous position of said beam on said region, and output means coupled to said target and responsive to said variations of potential.

11. A device of the character described in claim 10 in which said means for causing the potential of said target to vary as a function of the instantaneous position of said beam on said region comprises a shield positioned to intercept different proportions of said beam at different positions of said beam, the resultant variation in each of said regions corresponding to a different component of speech.

12. A device of the character described comprising a control element having recorded thereon two separate complementary series of indicia comprising contrasting areas of different light transmission properties, photoelectric means associated with each series of indicia for producing output voltages varying in magnitude in accordance with each successive indicium, said control element and said photoelectric means being relatively movable, means controlled by each

output voltage for producing a separate control voltage corresponding to each indicium, a cathode ray tube having a cathode beam and a target, said target being subdivided into a plurality of regions extending laterally across said target, means controlled by unique combinations of one control voltage corresponding to an indicium of each of said series for causing said beam to impinge on a given region of said target and to sweep once over the length thereof, means associated with each of said regions for causing said beam to modulate distinctively the potential of said target within an audio frequency range, and output means coupled to said target, whereby the successive distinctive audio frequency modulations of said target potential are produced in a predetermined time sequence determined by the pattern of said complementary indicia.

13. A system for artificially reproducing speech comprising tone generator means for individually reproducing the basic tones and sounds comprising the spoken language, means for selecting and combining the sound components in a controlled time sequence to reproduce artificially intelligible words comprising a programming device responsive to a predetermined limited number of coded indicia in two distinct series, means for deriving a controlling potential corresponding to each of said indicia, a plurality of control tubes corresponding in number to said series of basic tones for controlling said generator means, and a resistance control matrix coupling said control tubes to said control potential deriving means.

14. In a speech reproduction system, the combination of a plurality of tone generating means corresponding in number to the basic tones and sounds comprising a spoken language and being at least thirty-five in number, a control element having recorded thereon two separate series of coded indicia each less than six in number, means separately responsive to each of said series of indicia for producing a separate control voltage corresponding to each indicium, and control means for each of said tone generating means responsive to a predetermined one of a combination of said control voltages corresponding in number to the total of said tone generating means.

LESLIE E. FLORY.
